(57) **CLAIM**

We claim the ornamental design of a universal serial bus interface housing for communications devices, as shown and described.

DESCRIPTION

FIG. 1 is a front, right 3/4 perspective view of the universal serial bus interface housing showing our ornamental design. FIG. 2 is a top plan view of the interface housing. FIG. 3 is a bottom plan view of the interface housing. FIG. 4 is an elevational view of the left side of the interface housing; the right side is identical; and, FIG. 5 is an elevational view of the front end of interface housing; the rear end is identical.
